UNITED STATES PATENT OFFICE.

EDWARD A. LANGENBACH, OF CANTON, OHIO.

DESIGN FOR A BORDER-PLATE.

SPECIFICATION forming part of Design No. 26,243, dated November 3, 1896.

Application filed September 23, 1896. Serial No. 606,785. Term of patent 7 years.

To all whom it may concern:

Be it known that I, EDWARD A. LANGENBACH, a citizen of the United States, and a resident of Canton, county of Stark, State of Ohio, have invented and produced a new and useful Design for Metallic Border-Plates, of which the following is a full, clear, and exact description, reference being had to the accompanying drawings, making part of this specification.

My invention relates to a new design for metallic borders; and it consists of a plate of the form and ornamentation shown in the accompanying drawings, in which—

Figure 1 is a plan view of the border, and Fig. 2 is a sectional view.

The leading feature of the design is a rectangular plate A, curved transversely of its length and formed by ribs a into panels 1, 20 the fields of which are provided with closely

and irregularly arranged hair-lines and with grotesque figures 2, having scaled conical bodies and leaf-shaped tails and separated by shields 3, composed of alternating raised and sunken portions 4 and 5, respectively. 25

A border ornamented as above described and as shown in the accompanying drawings has a pleasing effect to the eye and adds greatly to the general appearance of the room or hall where used. 30

What I claim is—

The design for a metallic border as herein shown and described.

In testimony whereof I have hereunto set my hand this 30th day of July, A. D. 1896.

EDWARD A. LANGENBACH.
